UNITED STATES PATENT OFFICE

2,116,241

PROTECTOR

John P. Heumann, New York, N. Y.

Application May 6, 1935, Serial No. 19,997

3 Claims. (Cl. 128—139)

The protector of this invention is a shield guarding orifices of the body, such as mouth and nose, and also serves to support filters, absorbents, medicaments, inhalants, disinfectants or germicides to be applied to said orifices.

It is one object of this invention to intercept direct or straight access to the said orifices.

I further arrange my protector so as not to impede breathing or speech.

10 Another object of my invention provides for properly positioning or securing the protector.

Still another object of my invention provides for means securing suitable carriers for medicaments etc. on the protector.

15 These and other objects of my invention will be more clearly recognized from the following description in connection with the appended drawing, in which:

Fig. 1 shows a back view of a protector of my invention.

20 Fig. 2 shows a corresponding central cross-section.

Fig. 3 indicates the back view of a symmetrical half of a modification of my protector.

25 Fig. 4 shows a corresponding central cross-section.

Fig. 5 is a back view of another modification of my invention.

Fig. 6 is a corresponding central cross-section.

30 Fig. 7 illustrates, in a detailed view, an adjustable holding feature used for my protector.

Fig. 8 shows a cross-section of another arrangement of my protector.

Fig. 9 is the back view of another modification 35 of my protector.

Fig. 10 is a corresponding central cross-section.

Fig. 11 illustrates the use of a protector of my invention.

Similar numerals refer to similar parts 40 throughout the various views.

The shield of my protectors is generally made of stiff, flexible material, Celluloid for instance. In certain instances, for instance where it is folded over and engages upon fabrics slid thereunder, I rely on the resiliency of the material of the shield, for the purpose of clamping, stretching or detachably holding the fabric.

45 The shield S of Figs. 1 and 2 is shaped and perforated so that it may be positioned over the mouth and nose, in the position indicated in Fig. 50 11 by means of a suitable string or elastic slung through such perforation. Along the central, part the top and bottom edges 16 and 17 are folded back onto the shield. A piece 18 of gauze 55 or absorbent or medicated material may be

slipped underneath the folded-over part 16 and 17 and will be clampedly engaged thereby upon the back of the shield S. The air inhaled or exhaled by the user of my protector will flow over and contact the piece 18, which absorbs or mediates foreign matter. The piece 18 may contain medicaments or disinfectants which slowly evaporate or volatilize and/or absorbent liquid may be applied thereto.

10 In the modifications of Figs. 3 and 4 suitable hooks 19 take hold of the material of the shield S, and extend up and down from the edges of the folded-over parts 16 and 17 in the back of the shield. The absorbent material or gauze 20 is perforated, and through the perforations extend 15 the hooks 19 so that the material 20 is stretched in the back of the shield S, in front of the nasal and/or oral orifice.

Instead of providing eyelets in the shield for the purpose of extending a string or an elastic 20 therethrough, around the head or over the auricle, ear 21 may be suitably attached to the shield, on opposite sides thereof, then fastening means are slung therethrough around the head or over the ear, or a bow 22, is passed therefrom 25 over the root of the auricle.

The bow 22 comprises a tube 23, which is exemplarily close, flattened and transversely perforated at one end where it is linked to the ear 21. Into the open end of the tube 23 slidably extends the straight end of the hook 24. The hook 24 may be provided with a flat, perforated end 25, a looped wire 26 suspendedly extending through said perforation.

30 The free ends of the wire 26 may be bent back 35 upon themselves, and it is preferably made of a flat spring or resilient wire, so that it normally assumes the shape indicated in Fig. 7.

The free ends of the wire 26 may be momentarily pressed together, inserted in the tube 23 40 ahead of hook 24, and the released wire will frictionally engage upon the inside of the tube, as indicated in Fig. 5, so that the hook 24 is normally securely positioned in the tube 23, but may be adjusted therein, in order to provide for the 45 correct length of the bow, as required by the individual user in securing the shield in a position in which it is strapped without undue pressure over mouth and nose, resting upon the chin, the bow retracting the lateral ends of the shield. 50

The modified protector of Fig. 5 adds the horizontal platform 28 as an extension of folded back part 16 of the shield S. The free end 29 of the platform is folded back over the platform, and provides a clamping or engaging means for ab- 55

sorbent material 30. Under these circumstances the material 18 protects the mouth only, the material 30 protecting the nose.

Hook 31 may be cut out of the shield S in the plane thereof, as indicated in Figs. 9 and 10. The gauze 32 is strapped over the hooks 31 in a manner analogous to the modification of Figs. 3 and 4. The corners 33 of the gauze will then be disposed to the front of the shield. The folded 10 back bottom edge 17 may be used in connection with this arrangement, as in the prior modifications, in order to prevent a cutting of the chin.

Hooks 34, similar to the hook 19 of the modifications of Figs. 3 and 4, and to the hook 31 of Figs. 9 and 10, are applied to the modification of Figs. 5 and 6, the absorbent material may be strapped over the said hooks 34 and will then extend over the back of the platform 28, as indicated in Fig. 8, thus being closer to the nose and 20 to the mouth. The gauze or absorbent material 18 may be dispensed with under these circumstances, or it may be provided, and may for instance be medicated, the medicament contained therein reacting through the gauze 35. The back 25 edge 36 of the platform 28 is shown to be folded down.

It should be noticed that the folded over edges like 16 and 17 reduce the transverse flexibility of the material of the shield, particularly when the 30 absorbent material is wedged therebelow. I thereby gain the advantage, that the shield, particularly adjacent to the mouth and the nose, does not lie flatly against the face, but provides for a certain amount of clearance, which offers ample space for circulation of the air to be 35 breathed in and out.

When, however, more circulation of air is required, or the shield lies too close to the skin, as might for instance be the case in the arrangement

of Figs. 9 and 10, because there the upper edge is not reinforced, the shield may be suitably perforated as indicated at 37, in Fig. 9.

Although I have shown and described one form of embodiment of my invention in detail, yet I 5 do not wish to be limited thereby, except as the state of the art and the appended claims may require, for it is obvious that various modifications and changes may be made in the form of embodiment of my invention, without departing 10 from the spirit and scope thereof.

What I claim is:

1. In a protector for mouth and nose, absorbent material, a flexible shield with a bent-over edge formed in the material of said shield and supporting said material, and elongatable bows extending from said shield adapted to fit over the ears, so that said bows may be set to flex said shield over mouth and nose and then said edge will clamp onto said shield a piece of said absorbent material inserted thereunder. 15 20

2. In a protector for mouth and nose, absorbent material, a flexible shield supporting said material, bows extending from said shield adapted to fit over the ears, telescoping members in said 25 bows, and a spring attached to one such member and frictionally but slidably engageable upon another one of said members.

3. In a protector for supporting absorbent material in front of nose and mouth, an uninterrupted flexible shield adapted to rest upon the tip 30 of the nose and upon the chin, a platform extending like the center leg of a T from the back of said shield, so that it may extend underneath the nose, and means for engaging and stretching 35 said material from the top to the bottom of said shield over said platform.

JOHN P. HEUMANN.
